[57] CLAIM

The ornamental design for a combined fireplace cooking accessory tool set and support stand therefor, as shown and described.

DESCRIPTION

FIG. 1 is a front elevation view of a combined fireplace cooking
accessory tool set and support stand therefor
showing my new design with the two left hand notches
and apertures shown broken away and partially in section for clarity of illustration;

FIG. 2 is a top plan view thereof;

FIG. 3 is a bottom plan view thereof; and

FIG. 4 is a side elevation view thereof.
